UNITED STATES PATENT OFFICE.

ELLEN EVEREST RICHARDSON, OF BOSTON, MASSACHUSETTS.

LACE-FASTENER.

1,241,021.

Specification of Letters Patent. Patented Sept. 25, 1917.

Application filed February 19, 1917. Serial No. 149,588.

To all whom it may concern:

Be it known that I, ELLEN E. RICHARDSON, a citizen of the United States, residing at Boston, in the county of Suffolk and 5 State of Massachusetts, have invented certain new and useful Improvements in Lace-Fasteners; and I do declare the following to be a full, clear, and exact description of the invention, such as will enable others 10 skilled in the art to which it appertains to make and use the same.

One object of the present invention is to provide an extremely simple and inexpensive fastener for lace and the like which is 15 wound on cards, it being the intention to render the use of pins unnecessary.

Another object is to connect the fastening strap employed with the card in such a manner as to permit it to swing entirely 20 free of the lace when winding or unwinding so that there is no danger of winding the material around the strap. In this connection, a further object is to form the fasteners of the strap so as to permit them to serve 25 as pivots and yet prevent the strap from being accidentally detached from the card while winding or unwinding the lace after one end of said strap has been loosened.

Yet another object is to carry part of the 30 fastening means by the strap and part by the card and to so locate the fastening means on the latter as to coöperate with the jaws which hold and turn the cards while they are being wound at the factory.

35 With the foregoing objects in view, the invention resides in the specific arrangement of parts hereinafter fully described and claimed and shown in the accompanying drawing wherein:—

40 Figure 1 is a plan view of a card of lace showing the improved fastening means in operative position;

Fig. 2 is a similar view showing the fastening strap swung free of the lace; and,

45 Fig. 3 is an edge view with parts broken away—and in section to more clearly show the fastening means of the strap.

In the drawing above briefly described, the numeral 1 has reference to a one-piece 50 rectangular card upon which lace or the like 2 is wound, the ends of said card projecting beyond the lace as shown. Heretofore it has been the common practice to pin the free end 3 of the lace when shipping it 55 from the factory or after unwinding it when making a sale. The present invention,

however, is so constructed as to obviate the trouble of pinning the lace and to hold the entire quantity thereof in orderly fashion on the card.

60 A fastening strap 3 preferably formed of a single length of elastic is provided to extend longitudinally of the card 1 over the lace wound thereon and by means of snaps such as those commonly used for fastening gloves, the ends of said strap are detachably secured to the card. The male sections 4 of said snaps are carried by the 65 ends of the strap whereas the female sections 5 are secured in openings in the ends 70 of the card 1, this arrangement of the sections 5 being advantageous for a purpose to be described.

75 When the lace is wound on the card at the factory, the free end thereof is held in place by the strap 3 and when said lace is to be unwound, the snap at one end thereof is loosened so that said strap may swing to the position of Fig. 2, the other snap serving as a pivot for permitting this movement although it will also prevent accidental detachment. It is preferable to operate the device in this manner, although if desired, the strap may be held away from the lace by the 80 thumb of the salesman. When the strap is 85 swung to the position indicated in Fig. 2, there is no danger of covering any portion of the same with the lace when rewinding the latter in case too much thereof has been 90 unwound. When said strap is returned to 95 its normal position, however, the lace will be held in orderly fashion on the card.

From the foregoing it will be observed 100 that although the invention is of extremely simple nature and may be manufactured at a minimum cost, it will be a highly efficient article. Particular emphasis is laid upon the fact that either of the snap fasteners will act to release one end of the strap and that the other will then serve as a pivot that will 105 not permit accidental detachment of the entire strap. Particular stress is also laid upon the fact that the female sections 5 of the snaps or fasteners are carried by the ends of the card 1. By this arrangement, the jaws in which said ends of the card are held when winding the lace at the factory may well be equipped with detents for reception in said sections and thus the card will be effectively held against dislocation. Furthermore, when the cards are manufactured, the sections 5 will not protrude there- 110

from an undesirable amount and thus they may be compactly stacked and packaged.

I claim:—

An article of manufacture comprising a card upon the body portion of which a strip of lace is adapted to be wound, a fastening strap at one side of said card for anchoring the strip, and snap fasteners at the ends of the card for securing the ends of said strap detachably and pivotally thereto, the female sections of said fasteners being in the form

of metal eyes extending entirely through the cards and substantially flush with the sides thereof.

In testimony whereof I have hereunto set my hand in the presence of two subscribing witnesses.

ELLEN EVEREST RICHARDSON.
